CLOSURE FOR CARTONS

Ernest J. Biskamp, San Antonio, Tex.

Application December 16, 1943, Serial No. 514,532

2 Claims. (Cl. 229—17)

1

This invention relates to cardboard boxes or cartons of the folded blank, tubular type, and particularly to such cartons as are commonly employed for the packaging of granular or finely divided fluent material.

Numerous attempts have heretofore been made to provide suitable pouring openings for such cartons, but most of these have proven unsatisfactory, either because, having once been opened, it was impossible to close them again, or for other practical reasons.

The object of the present invention is to provide a carton of the above type having a closure section constituting means forming a pouring opening, such closure sections being so constructed that it may be replaced and retained in closed position.

A further object is to provide such a closure which may be opened and closed as often as desired and which will remain operative for the life of the carton.

A still further object is to provide closure means of the above character which may be readily formed as an integral part of the usual commercial box blank, and which entails substantially no additional expense in the manufacture and assembling of such blanks.

In order that the invention may be readily understood, reference is had to the accompanying drawing, forming part of this specification, and in which

Fig. 1 is a view of folded box blank embodying my invention, parts being broken away.

Fig. 2 is a fragmentary vertical section on an enlarged scale through the corner portion of the box containing my improved closure, the closure being illustrated in partially opened position, and parts being shown in dotted lines.

Fig. 3 is a perspective view of the corner of the box containing my improved closure, the closure being shown in fully opened position, and

Fig. 4 is a similar view, the closure being shown as it appears after having been opened and replaced in closed position.

Referring to the drawing in detail, and more particularly first to Fig. 1 thereof, the blank comprises the usual panels 1 and 2, constituting the side walls of the box, and the panels 3 and 4, constituting the edge walls, together with outer and inner end flaps 5, 6, 7 and 8, adapted to be folded over in superposed relation to constitute the end walls. The blank is also provided with the usual lip 9 by which the two edges of the blank are secured together when the box is assembled.

2

My improved closure comprises a section 10, hingedly connected by means of a score line 11, with one of the edge walls 4, this score line being located a substantial distance from the end of the box. The section 10 is defined by perforated lines 12 and 13, the former coinciding with the fold lines between the edge wall 4 and the side walls 1 and 2, and the latter coinciding with the fold line between the edge wall 4 and the associated end flap 8. Thus, the section 10 extends the full width of the edge wall 4.

Projecting from the side of the section 10, opposite the score line 11, is a tab 14, hingedly connected with the section 10 by means of a score line 15. This tab 14 normally lies in the plane of the flap 8 and is separated therefrom by means of an arcuate cut 16, which extends entirely through the thickness of the cardboard. Thus, this tab is free at all points, except where it joins the section 10 at the score line 15.

The blank, having been cut and scored as described, is then folded to form the carton in the usual manner, the end flap 8 being preferably folded on the inside, as indicated in Fig. 2. It will be understood that the outer surface of the tab 14 is so treated that the cement used to secure the superposed end flaps together will not adhere to it. When it is desired to open the box to pour out a portion of the contents, the section 10 is broken loose along the perforated lines 12 and 13, as by means of the thumbnail or other sharp instrument, and, the tab 14 being entirely free from connection with the box walls, the section 10 may be swung downwardly about the score line 11, as shown in Figs. 2 and 3, to provide a pouring opening.

As indicated in Fig. 2, the tab 14, after having been withdrawn from the box, may be swung around the score line 15 into the position shown in dotted lines, and this is preferably done before any material is poured. Thus the section 10 provides a guide along which the material may flow, as it is poured out, and the tab, when bent as shown, does not interfere with the free flow of the material over such section.

When it is desired to close the pouring opening, the section 10 is swung back about the line 11 to its original position and is then pushed slightly inwardly beyond such position, as illustrated in Fig. 4. When this is done, it will be seen that the edges 12 of the section 10 frictionally engage the inner surfaces of the side walls 1 and 2, due to the fact that the section 10 is of the full width of the edge wall 4. In most cases it is even probable that, owing to the fact that the

perforated lines 12 coincide with the fold lines between the box walls, the section 10, with its more or less ragged edges, is even slightly wider than the space between the inner surfaces of the side walls and consequently when it is forced between them, makes a rather tight fit. The edges 13 of the section 10, when in the position shown in Fig. 4, also frictionally engage the inner surface of the top flap 8.

It will be noted that the tab 14, having been swung to the dotted line position, shown in Fig. 2, now projects outwardly from the section 10 and constitutes a handle by means of which the section may be manipulated, and by means of which the closure may be readily withdrawn from the closed position, shown in Fig. 4. Moreover, in this closed position, the tab itself likewise tends to frictionally engage the end wall of the box and thus aids in maintaining the closure in closed position.

In operation, the user grasps the tab 14, when moving the closure to closed position, and the ends of the user's fingers, engaging the edge of the end wall of the box, constitute a stop to limit the extent to which the section 10 may be pushed inwardly. When operated in this manner, as intended, there is no danger of pushing the section in too far.

While in the specification I have referred to the lines 12 and 13 as "perforated," it will of course be understood that any other desired form of weakening may be employed.

Also, while I have shown the walls 3 and 4 as narrower than the walls 1 and 2, and have referred to the walls 3 and 4 as "edge walls," it will be understood that the invention is equally applicable to cartons in which all of the walls are of the same width. Consequently, all may be designated "side walls."

What I claim is:

1. A blank for forming foldable boxes of the tubular type, said blank comprising side and edge panels and end flaps, said side and edge panels

being separated from each other and from said end flaps by fold lines, one of said edge panels having at one end a rectangular closure section defined on two sides by perforated lines coinciding with the fold lines between said edge panel and adjacent side panels, and partially defined on a third side by a perforated line coinciding with the fold line between said edge panel and adjacent end flap, and a tab cut out of said end flap and projecting from said third side of said section, and said section being connected at its fourth side with said edge panel by means of a score line.

2. A carton having side walls, and end walls comprising superposed inner and outer flaps, said side walls being separated from each other and from said flaps by fold lines, one of said side walls having adjacent its end a rectangular section defined by perforated lines coinciding with the fold lines between said side wall and the two adjacent side walls, and between said side wall and said end wall, said section being hingedly connected by a score line along its side remote from said end wall with said side wall, and said section being provided at its opposite side with a projecting tab cut out of the inner flap of said end wall, said tab being hingedly connected at one edge with said section and having its other edges entirely free, and said tab originally lying wholly within the carton and being covered by the outer flap of said end wall, whereby, when said perforated lines are broken, said section may be swung outwardly about said score line to provide a pouring opening and may be swung back into closed position, and whereby said tab may be swung so as to project outwardly, to constitute a handle by means of which said section may be manipulated, the edges of said section, and the tab carried thereby, when pushed slightly inwardly, frictionally engaging the inner surfaces of said side and end walls and thus retaining said section in closed position.

ERNEST J. BISKAMP.
